UNITED STATES PATENT OFFICE

155,092

DESIGN FOR AN EGG CARTON

James Warren Lennon, St. Paul, Minn., assignor
to Fibre-Plastics Corporation, Minneapolis,
Minn., a corporation of Minnesota

Application May 3, 1947, Serial No. 138,789

Term of patent 14 years

(Cl. D58—13)

To all whom it may concern:

Be it known that I, James Warren Lennon, a citizen of the United States, residing at St. Paul, county of Ramsey, and State of Minnesota, have invented a new, original, and ornamental Design for an Egg Carton, of which the following is a specification, reference being had to the accompanying drawing, forming part thereof.

Figure 1 is a top plan view of an egg carton showing my new design; and

Figure 2 is a sectional view thereof taken on the line 2—2 of Figure 1.

I claim:

The ornamental design for an egg carton, as shown.

JAMES WARREN LENNON.
